United States Patent Office

Des. 180,948
Patented Sept. 10, 1957

180,948

SLACK SUIT

Mildred B. Gauthier, Fontana, Calif.

Application May 4, 1956, Serial No. 41,338

Term of patent 3½ years

(Cl. D3—17)

I claim:

The ornamental design for a slack suit, as shown.
